HENRY BERNON TOURTELLOT, OF QUINCY, MASSACHUSETTS, ASSIGNOR TO AMERICAN CAN COMPANY, OF NEW YORK, N. Y., A CORPORATION OF NEW JERSEY.

CIGAR-DISPLAY HUMIDOR.

1,129,921.

Specification of Letters Patent. Patented Mar. 2, 1915.

Application filed February 3, 1913. Serial No. 745,842.

To all whom it may concern:

Be it known that I, HENRY BERNON TOURTELLOT, a citizen of the United States, residing in Quincy, in the county of Norfolk and State of Massachusetts, have invented 5 a new and useful Improvement in Cigar-Display Humidors, of which the following is a specification.

This invention relates to an improvement 10 in display humidors for cigars, and it consists in the novel devices and combination of parts and devices hereinafter described and made the subject matter of claim.

In the accompanying drawing which 15 forms a part of this specification, Figure 1 is a longitudinal section of the improved humidor, the same being shown closed and standing flat. Fig. 2 is a cross sectional elevation, showing the humidor erected into 20 the display position. Fig. 3 is a bottom or plan view,—upon a somewhat smaller scale,—of the humidor as shown in Fig. 1.

A purpose of the invention is to provide 25 a humidor of suitable size to receive a cigar box and its contents of cigars, such humidor also to contain the necessary moistening pads; to be furnished with the glass hinged lid to close the same for the retention of 30 the moisture; and to be furnished with a means for tilting and sustaining the humidor in display position, and for holding advertising matter.

In the drawing, A is a sheet metal, wood or fiber box, the bottom B of which is 35 flanged with a flange b interfolded with the sides of the box, and thus forming at the bottom a countersunk portion B¹, which serves to strengthen the structure and at the same time to receive and contain a folded 40 display stand consisting of the frame C, pivoted at c to the bottom of the box, and pivoted at c¹ to the swinging plate D formed with a hook or offset d into which hook, as shown in Fig. 2, the edge of the 45 inclined box may be placed and securely held in the display position against movement in either direction. If, for any purpose, it is desired that the humidor shall stand flat, the display stand is folded up 50 upon itself and will then be contained, as indicated in Fig. 1, entirely within the countersunk bottom. The upper edge of the humidor box is all around formed with an

inwardly and downwardly extended flange a which serves to stiffen and strengthen the 55 structure, and also as a holding place or receptacle for the necessary humidor pads. The humidor pads are preferably made of perforated metal and blotting paper, the latter E held between two sheets of the 60 former F, and stiffened at the edges by interturned flanges f. The perforated metal should preferably be coated with waterproofing enamel or varnish to guard against rusting. When these moistening pads 65 have been soaked with water, they can be placed in the humidor and removably held therein by tilting them in the position shown in dotted lines in Fig. 1, and then pushing them into the vertical position, 70 when the inward and downward turned flange a at the top of the humidor box will serve to retain the pads in the vertical position against displacement. These pads may be placed one at each end or, in addition 75 thereto, at the long sides of the box, as desired, the downwardly and interturned flange a serving as a holding means in either position.

When the humidor is in the display position supported upon the display stand, the 80 upwardly extending leaf D¹ of this stand serves as a rest, upon which may be supported the hinged glass cover G, as indicated in dotted lines in Fig. 2, so that the humidor may be easily kept open when desired. The upwardly extending leaf D¹ 85 and the support also offer a convenient place to hold a price card or other advertising card, or, if desired, the top of the wooden cigar box, removed from said box, may be 90 placed therein.

Having described the invention, that which is claimed is:

An article of manufacture comprising, in combination: a container adapted to serve 95 as a humidor and having a body provided with a cover, the body having an inwardly extending and downwardly turned flange around the top thereof between which and the walls of the body is adapted to be received an edge of a moistener pad, substantially as specified.

HENRY BERNON TOURTELLOT.
